Edwin A. Palmer.

United States Patent Office.

EDWIN A. PALMER, OF CLAYVILLE, NEW YORK.

Letters Patent No. 79,250, dated June 23, 1868; antedated June 12, 1868.

IMPROVEMENT IN CHEESE-CURD RAKES.

The Schedule referred to in these Letters Patent and making part of the same.

TO ALL WHOM IT MAY CONCERN:

Be it known that I, EDWIN A. PALMER, of Clayville, in the county of Oneida, in the State of New York, have invented a new and useful Improvement on a Cheese-Curd Rake; and I do hereby declare that the following is a full, clear, and exact description of the construction and operation of the same, reference being had to the annexed drawings, making a part of this specification, in which—

Figure 1 is a perspective view.

Figure 2, a longitudinal elevation of the head.

Figure 3, a transverse section.

The same letters refer to the same parts.

A is the lower head of the rake, thirteen inches long, two inches wide or high, and five-eighths of an inch thick, except at E, where the handle E passes through, which is one inch thick.

B B are the teeth, sixteen in number, fifteen inches long, of galvanized wire one-eighth of an inch in diameter, set in the head at equal distances apart.

C is the upper head or support for the top of the teeth, which cannot be used without it, on account of the teeth being small and long. It is important that the teeth be long to reach up through the curd.

D D are braces, which pass through the handle E, and up to the ends of head C, and secured there for the support of the teeth also.

The head C is thirteen inches long, five-eighths of an inch in diameter. The handle E is three and a half feet long, one and one-eighth of an inch diameter.

F F are pins, of wood, in the lower edge of the head A, half an inch long, to keep the head from resting on the bottom of the vat. The heads and handles are made of hard wood. The braces are of wire, same as the teeth.

The rake is used to raise the curd, after it is checked. It saves the use of the knife to cut it fine; and also to stir the cheese-curd while it is scalding, and being prepared for the press.

I do not claim any part of the common rake, with short wood or metallic teeth or braces to support the lower head, the same being in use, neither any principle involved in the agitator; but

What I claim as my invention, and desire to secure by Letters Patent, is—

The upper head C, and the braces D D, or their equivalent, for the purpose therein described and set forth.
